UNITED STATES PATENT OFFICE.

ISAAC G. STEVENS, OF ROCHESTER, NEW YORK, ASSIGNOR TO THE YAWMAN & ERBE MANUFACTURING COMPANY, OF ROCHESTER, NEW YORK, A CORPORATION OF NEW YORK.

DESIGN FOR A WATCH-FOB, PENDANT, OR SIMILAR ARTICLE.

49,043.

Specification for Design.

Patented May 9, 1916.

Application filed February 25, 1916. Serial No. 80,535. Term of patent 14 years.

To all whom it may concern:

Be it known that I, ISAAC G. STEVENS, a citizen of the United States, residing in Rochester, in the county of Monroe and State of New York, have invented a new, original, and ornamental Design for a Watch-Fob, Pendant, or Similar Article, of which the following is a specification, reference being had to the accompanying drawing, forming a part thereof.

The figure is an elevational view of a watch fob pendant showing my new design.

I claim:

The ornamental design for a watch fob, pendant, or similar article as shown.

ISAAC G. STEVENS.

Witnesses:

FRANCIS J. YAWMAN,
W. F. WARNER, Jr.
